(57) **CLAIM**

We claim the ornamental design for a flashlight, as shown and described.

DESCRIPTION

The file of this patent document contains at least one drawing executed in color. Copies of this patent document with color drawings will be provided by the United States Patent and Trademark Office upon request and payment of the necessary fee.

FIG. 1 is a perspective view of a flashlight according to one embodiment.

FIG. 2 is a first side view of the flashlight of FIG. 1.

FIG. 3 is a second side view of the flashlight of FIG. 1.

FIG. 4 is a third side view of the flashlight of FIG. 1.

FIG. 5 is a fourth side view of the flashlight of FIG. 1.

FIG. 6 is a first end view of the flashlight of FIG. 1.

FIG. 7 is a second end view of the flashlight of FIG. 1.

FIG. 8 is a perspective view of a flashlight according to another embodiment.

FIG. 9 is a first side view of the flashlight of FIG. 8.

FIG. 10 is a second side view of the flashlight of FIG. 8.

FIG. 11 is a third side view of the flashlight of FIG. 8.

FIG. 12 is a fourth side view of the flashlight of FIG. 8.

FIG. 13 is a first end view of the flashlight of FIG. 8; and,

FIG. 14 is a second end view of the flashlight of FIG. 8.

The broken lines in the drawings depict portions of the flashlight that form no part of the claimed design.
